(57) **CLAIM**

The ornamental design for an ink cartridge, as shown and described.

DESCRIPTION

FIG. 1 is a perspective view of an ink cartridge, as viewed from the front, top, and left side, embodying our design; FIG. 2 is a perspective view thereof, as viewed from the front, bottom, and left side;

FIG. 3 is a front of thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines represent unclaimed subject matter, or unclaimed depth (in the case of dotted lines within solid outlines), and form no part of the claimed design.
